WATER HEATING SYSTEM

David L. Buchanan, White Marsh, Pa., assignor
to Edward G. Budd Manufacturing Company,
Philadelphia, Pa., a corporation of Pennsylvania

Application May 1, 1936, Serial No. 77,304

6 Claims. (Cl. 237—12.4)

This invention relates to improvements in water heating systems for rail cars, more particularly of the electrically operated type as for example those having a self contained power plant 5 including an internal combustion engine and electric generator.

The development of non-steam powered rail cars and trains, especially of the self contained internal combustion engine type, has eliminated 10 the customary source of heat for the water required for bath and lavatory use, and although heat exchange units, arranged in connection with the main car heating plant, can supply the necessary heat in cold weather, and hot water can be 15 obtained from the air conditioning equipment in weather when it is in use as set forth in a copending application of Mayer, Serial No. 73,999, filed April 13, 1936 on Water heating system, there are many periods of the year during which adequate heat must be provided, and ordinarily at a 20 great sacrifice of fuel and costly operation of other equipment.

The principal object of my invention is to provide means for heating of water for bathing purposes on non-steam powered rail cars during the 25 temperate weather during which the normal air conditioning equipment is not operated, such heating being available as a by-product of the normal power source and thus not involving additional equipment or operating expense.

A further object of the invention is to provide 30 a combined hot water heating system for bath and lavatory purposes of an air conditioned rail car which includes a heat exchange device in the air conditioning refrigerant circuit using the sensible heat of the refrigerant when the air conditioning equipment is in use, and an electric immersion heater interlocked with the same power source as the air conditioning equipment for operation when the air conditioning equipment is not 35 in operation.

A still further object of the invention is to provide 40 a water heating system for non-steam operated air conditioned rail cars which includes interlocking relays controlled by a suitable thermostat for energizing an immersion heater when the water is below a predetermined temperature and the air conditioning compressor motor is de-energized, and for de-energizing the immersion heater either at the predetermined water temperature or when the air conditioning equipment 45 is operating so that the water will be maintained at the desirable high temperature and without additional power drain from the available rail car operating source.

Further objects and advantages of my invention will appear from the following description thereof taken in connection with the attached drawing, which is illustrative of a preferred form 5 of embodiment of the invention, such drawing being a diagrammatic arrangement of the water heating plant.

The non-steam type of train having air conditioning equipment commonly has a limited source 10 of electrical energy as from the power plant generally indicated at 10. Whether it be of the internal combustion engine type having a suitable generator or other source of electrical power, additional capacity is normally available to take care of the various auxiliaries, including the motor 12, which operate the air conditioning equipment in the respective cars. With normal refrigerating capacity of five or six tons per day, 15 motors of ten horse power are frequently used.

The air conditioning equipment in addition to the compressor 14 includes the condenser 16, refrigerant receiver 18, thermostatically controlled expansion valve 20, and evaporator 22, in which the car air is conveniently cooled. The refrigerant then returns to the compressor 14 as is well known. This refrigerant cycle is also conveniently provided with a heat exchanger 24 by which the water is heated during hot weather when the air conditioning system is in operation.

The water for bathing purposes may be conveniently heated in cold weather by a heat exchanger 26 in the main steam supply, which in a non-steam operated train is commonly derived from an independent furnace 28 as of the oil burning type. The water tank 30 containing the 30 adequate water for lavatory and bathing purposes is normally connected in heat exchange relation with this main steam line through the heat exchanger 26, and thence through heat exchanger 24, which are adequate to maintain the water hot 35 in either hot or cold weather. If desired, a circulating arrangement with respect to the heat exchangers and water reservoir 34 may be provided by suitably arranged piping.

During mild spring and fall weather, however, which in many parts of the country is a substantial length of time, neither the main heating source nor the air conditioning and cooling equipment is in operation, and at such time the water demand is still very great. I have 45 therefore in addition provided an immersion heater 32 of electric type which is adequate to heat the water reserve in reservoir 34, and sufficient to take care of the demands which will 50 normally be made on each car. The immersion 55

heater is of any suitable type of resistance unit of adequate capacity, and I find that the necessary power demand of such a heater is substantially less than that required by the motor 12 for the air conditioning equipment. No additional load on the main power supply whether it be the power plant 10 or power taken from a third rail or overhead line would occur, provided they are not operative simultaneously.

10 I prefer to provide a pair of relays 35 and 36 connected by a suitable interlock 37 so that the electrical immersion heater cannot be used at any time the air conditioning equipment is being operated. In other words, if the motor 12 should start up for air conditioning purposes, adequate heat would be obtained from the heat exchanger 24, but if the motor 12 is stopped and the water in reservoir 34 cools off, a thermostat 38 will operate relay 36 to energize the 15 immersion heater 32. The immersion heater will only operate when the water temperature drops below a certain predetermined point and the relay 36 is in an operative position as controlled by interlock 37 from relay 35. The necessary 20 electrical controls, being well understood in the art, are not shown either of the interlock or for the operation of the motor 12 of the compressor, which may suitably be under automatic control to meet the conditions of air cooling required 25 in the car.

It will thus be seen that no operation of the immersion heater can become an extra load on the power source or cause unnecessary expense or require any substantial increase in equipment. Adequate hot water will always be available, especially for bath and lavatory facilities. No additional weight is involved, as water reservoirs on the cars can be readily adapted for hot water storage.

40 While I have shown a preferred form of embodiment of my invention, I am aware that other modifications may be made, and I therefore desire a broad interpretation of my invention within the scope and spirit of the description 45 herein and of the claims appended hereinafter.

What I claim is:

1. A domestic hot water heating system for a rail car having an electrically energized air conditioning equipment which comprises a heat exchange device in heat exchange relation with heated parts of the air conditioning equipment, means to pass water through said heat exchange device for heat transfer, an electrically energized immersion heater in heat exchange relation with the water supply, and electrical interlock means between the electrically energized immersion heater and the electrically operated air conditioning equipment, operated by the electrically energized air conditioning equipment limiting the 50 operation of said immersion heater to periods when said air conditioning equipment is electrically deenergized.

2. A domestic water heating system for a non-steam operated rail car having a source of electrical power, an air conditioning system having a compressor operated from said electrical power source, a heat exchange device in said air conditioning system for water heating, an electrical immersion water heater, an electrical interlock 55 between said electrically operated compressor and said electrical immersion water heater, said interlock restricting the operation of said immersion heater to periods in between the periods of normal intermittent operation of said air con-

ditioning system compressor to prevent overloading of the electrical power source.

3. A water heating system for supplying hot water for lavatory and bathing purposes in a rail car having a source of electrical power, a water reservoir, a car heating mechanism and an electrically operated air conditioning mechanism in circuit with the electric power source, a heat exchange device in heat exchange relation with said car heating mechanism, a heat exchange device in heat exchange relation with said air conditioning mechanism, means to pass water through said heat exchange devices to a hot water reservoir, and an electrically operated immersion heater in said hot water reservoir and in circuit with said electric power source, said immersion heater circuit being interconnected with said air conditioning mechanism circuit whereby said immersion heater can only be energized from the electrical power source when the air conditioning system is inoperative, said heat exchange devices working alternatively, and said immersion heater complementing said heat exchange devices.

4. In a hot water heating system for a rail car having an air conditioning system including an electrically operated compressor and a hot water heating device in heat exchange relation with said system, the combination of an electrically operated water heating device and means to interlock said electrically operated mechanisms so that the electrically operated water heating device may be energized only when the electrically operated compressor is de-energized, said compressor being energized in accordance with the demands of the air conditioning system, and means to control the operation of the electrically operated water heating device in accordance with the water temperature.

5. In combination with a rail car having a car heating source and an air conditioning mechanism including an electrically operated refrigerant circuit and a water supply, heat exchange devices in heat exchange relation with the car body heating source and with the refrigerant circuit to heat said water supply, an electrically operated water heating device to complement the heat for said water supply, and means to energize said electrically operated water heating device when the other heat exchange devices are ineffective, and means to render said energizing means ineffective when the electrically operated refrigerant circuit is energized.

6. In combination with a rail car having a car heating source and an air conditioning mechanism including an electrically operated refrigerant circuit and a water supply, heat exchange devices in heat exchange relation with the body heating source and with the refrigerant circuit to heat said water supply, and an electrically operated water heating device to heat said water supply, and means to energize said electrically operated water heating device when the other heat exchange devices are ineffective, said means including a thermostat controlling said electrically operated water heating device and interlocking means between said electrically operated water heating device and said electrically operated refrigerant circuit whereby the operation of the refrigerant circuit will prevent operation of the electrically operated water heating device.
